UNITED STATES PATENT OFFICE.

BERNARD D. WILLIS, OF CHICAGO, ILLINOIS, ASSIGNEE TO AUTOMATIC ELECTRIC COMPANY, OF CHICAGO, ILLINOIS, A CORPORATION OF ILLINOIS.

SEMI-AUTOMATIC TELEPHONE SYSTEM.

1,306,826.

Specification of Letters Patent. Patented June 17, 1919.

Application filed July 7, 1913, Serial No. 777,659. Renewed April 28, 1919. Serial No. 293,343.

To all whom it may concern:

Be it known that I, BERNARD D. WILLIS, a citizen of the United States of America, and resident of Chicago, Cook county, Illinois, 5 have invented certain new and useful Improvements in Semi-Automatic Telephone Systems, of which the following is a specification.

My invention relates to improvements in 10 semi-automatic telephone systems in which automatic district exchanges are employed with a manual main exchange. In such systems, certain of the subscribers' lines, instead of terminating directly in a manual switchboard, terminate in automatic switches in a 15 district office, which automatic switches select a trunk line leading to the manual switchboard. Ordinarily, in such systems, when a subscriber whose line terminated at 20 the district office wished to call another subscriber whose line terminated in the same district office, it was necessary for the calling subscriber to first select a trunk leading to the manual switchboard, and then the operator connected this trunk with another trunk 25 leading to the district office, over which second trunk the automatic switches were operated to connect with the called line. It will thus be seen that in such a connection two 30 trunks between the district and main offices were employed.

It is the object of my present invention to provide means whereby the talking connection between two subscribers of a single district office is confined entirely to apparatus located at this district office, the trunk line extending to the main exchange or manual switchboard only being employed for talking purposes when the calling subscriber desires to establish a connection with a subscriber whose line terminates in some other exchange.

By my present invention a calling subscriber, upon initiating a call by removing 45 his receiver from the hook, operates his individual line switch to select an idle trunk which has a branch extending to the manual switchboard. Upon the seizure of this trunk a signal is displayed upon the switchboard 50 to indicate to the operator that a connection is desired. The operator then plugs in and, upon learning that the called subscriber is located in the same exchange as the calling subscriber, operates her impulse-transmitting device to transmit a series of impulses

back over the same trunk to operate automatic switches in the district office and thus establish connection with the called line.

My invention will be more clearly understood by reference to the accompanying 60 drawings, in which I have illustrated my invention in connection with automatic switches of well-known types.

In the drawings Figures 1 and 2 taken together show a complete circuit connection 65 established between a calling substation A (Fig. 1) and a called substation A' (Fig. 2) in a system embodying the principles of my invention.

In Fig. 1 there is shown a subscriber's 70 substation A the line conductors of which terminate in the individual or line switch D. The line switch shown at D is one of a group of similar line switches the plunger (not shown) of which engage a shaft and are 75 controlled by the operation of the master switch shown at E in such a manner that they are, when in normal position, held directly in front of the terminals of a trunk line leading through a group of relays F to 80 a selector switch H. At C there is shown a manual operator's cord circuit to which is added a calling device L. At I (Fig. 2) a connector switch is shown which is one of a group of connectors to which the selector H 85 has access. At D' a line switch is shown which is similar in all respects to the one shown at D. The substation A' is in all respects similar to the substation shown at A. The apparatus shown in both figures, with 90 the exception of the cord circuit C, is located in a district or sub-exchange, while the cord circuit C is located in the main exchange.

The substation A is of the usual common battery manual type, consisting of the receiver 180, transmitter 181, hook switch 182, condenser 183 and the ringer 184.

The line switch D and the master switch E are modified forms of the general type of line and master switches disclosed in British Patent No. 26,301 of 1906, issued to R. W. James, being, however, of the particular type shown in British patent to T. G. Martin No. 1419 of 1910. As herein represented, the line switch D comprises among 100 other details a plunger (not shown) attached to the end of a so-called plunger arm 10 which is controlled by a magnet 11. The magnet also controls the armatures 12 and 13 and is composed of four windings, namely, a 110

pull-down winding 14, a holding or cut-off winding 15, a line winding 16 and an auxiliary winding 17. The magnet 11 is suitably mounted on a bracket 18 on which are pivot-
5 ed the armatures 10, 12 and 13. The mag-
netic circuit of the two windings 14 and 15 is kept separate from that of the windings
16 and 17, so that the armatures at one end
10 of the magnet are not affected by the ener-
gization of the winding at the other end.
Only the winding 14 is strong enough to at-
tract the plunger arm 10 from its normal
position, but the winding 15 is strong enough
15 to hold it in an operated position after it has
once been drawn down by the winding 14.
When the plunger arm is attracted, the plun-
ger of the line switch is forced into the
bank of contact springs, forcing the springs
2, 4, 6 and 8 into contact with the springs
20 3, 5, 7 and 9, respectively. Although only
one set of springs (2-9) is shown, each line
switch D is provided with a number of such
groups, each group forming the terminal of
a trunk line leading to a group of relays F,
25 which relays are in turn connected directly
to a first selector H. The relays 21 and 22
are bridged across the trunk line leading to
the relays F in series with battery and be-
come energized upon the operation of the
30 line switch plunger upon the calling sub-
scriber removing the receiver from the switch
hook. These relays are the means of sup-
plying battery current to the calling sub-
scriber. The relay 23 is a slow-acting relay
35 the springs of which, and the springs of the
line-switching relay 24, control the circuit of
the line signaling relay 25. The circuit is
traced through the relay 26, the function of
which is to repeat the impulses created by
40 the calling device springs L. A condenser
27 is inserted in one line conductor (Fig. 1).
The complete operation of the group of re-
lays F will be explained later.

The selector H consists of the usual verti-
45 cal and rotary magnets 19 and 20 for the
purpose of raising and rotating the shaft
wipers 35, 36 and 37 onto an idle trunk line
leading to the connector I, the line relay 28,
the release relay 29 (which is slow acting),
50 private magnet 30, private relay 31, line
switching relay 24 and a rotary interrupter
relay 32. The selector H is also provided
with the usual side switch consisting of two
side switch wipers 33 and 34.

55 The connector I is somewhat similar to
that disclosed in United States Letters Patent
No. 815,176, granted March 13, 1906, to
Keith, Erickson and Erickson, the circuits,
however, being modified to adapt the switch
60 for use in this particular semi-automatic sys-
tem. Like the selector, the connector is pro-
vided with a shaft (not shown) carrying the
wipers 38, 39 and 40, which shaft is con-
trolled by the vertical and rotary magnets
65 41 and 42 through the medium of the line

relays 51^a and 52. The side switch, consist-
ing of the side switch wipers 43, 44, 45 and
46, is controlled by the private magnet 47 in
the usual manner. The connector is pro-
vided with a so-called back-bridge relay 48
70 through which the called subscriber is sup-
plied with talking current. This relay is
also the means of energizing the ringing cut-
off relay and closing the circuit of the relay
76 in the cord circuit C (Fig. 1) when the
75 called subscriber takes his receiver off the
switch hook to answer the call. Ringing
current is supplied to the called line by
means of the ringing relay 51. A busy tone
current is sent back over the line to the call-
80 ing subscriber by the energization of the
busy relay 53. 54 and 55 represent the usual
release magnet and relay, the former oper-
ating to release the connector switch in the
well-known manner.

85 The line switch D' is exactly the same as
the line switch D and although the master
switch for controlling the group of line
switches to which the switch D' belongs is
not shown, it can be of the same type as the
90 master switch E.

Having given a general description of the
apparatus involved in my invention, I will
now explain how a subscriber at the sub-
station A obtains connection with a sub-
95 scriber at the substation A'. We will as-
sume that the number of the subscriber at
the substation A' is 220. Upon the sub-
scriber at the substation A taking his re-
ceiver off the switch hook, a circuit is closed
100 through the line winding 16 of the indi-
vidual switch D from ground G² through
contact of the springs 57 and 58, conductor
59, through the telephone and back over the
conductor 60, through contact of the springs
105 61 and 62 and through the winding 16 to
battery B. Upon the line winding becoming
energized, the armature 12 operates to
close the springs 63 and 67, thereby closing
a circuit from ground G² through the pull-
110 down coil 14 and through the auxiliary
winding 17 and the contact 200 to battery B
and to ground G. The winding 14 energizes
and attracts the plunger arm 10, together
with the armature 13, which latter breaks
115 the contact of the springs 61 and 62, 57 and
58, thus opening the circuit of the line
winding 16, the armature of which, how-
ever, does not fall back at this time, because
the auxiliary winding 17 is still energized
120 in series with the winding 14. Upon the
plunger arm 10 being completely drawn
down, the plunger of the line switch is
thrust into the bank terminals, pressing the
springs 2, 4, 6 and 8 into contact with the
125 springs 3, 5, 7 and 9, respectively. By the
same operation the springs 64 and 65 make
contact to short-circuit the auxiliary wind-
ing 17, which allows its armature to fall
back, opening the circuit of the pull-down
130

winding 14. This does not take place, however, until after the hold-down coil 15 has been energized by a circuit over the release trunk 66 from ground G^3 .

5 Upon the springs 2 and 4 making contact with the springs 3 and 5, the line connection is extended to the two line relays 21 and 22 of the group of relays F, which thereupon energize. The relay 21, upon energizing, 10 operates its springs to complete the circuit of the holding coil 15 from ground G^3 through the contact of the springs 67, springs 7 and 6 and through the winding 15 to the battery lead 100. The relay 22, upon 15 energizing, closes a circuit through the slow-acting relay 23 traced from ground G^4 , springs 152, and relay 23 to the battery B. Upon the energization of the relay 23, a circuit is closed from the battery lead 100 20 through the springs 68, springs 69 and 70, relay 26, conductor 91, contact 73 of the answering jack J and through the pilot relay 25 to ground G^5 . Upon the relay 26 energizing, the circuit of the relay 28 is 25 closed from ground G^3 , contact of springs 78 and through the relay 28 to the battery lead 100. The relay 28, upon energizing, operates its armature to close the circuit of the slow-acting relay 29, which in turn operates 30 its springs to prepare a circuit for the vertical and rotary magnets 20 and 19, the former through the contact 151 and the latter from ground G^{22} through the contacts 153 and 154 and through the interrupter 35 relay 32 to the rotary magnet. These circuits will be mentioned again later, as at this time they are still open. Upon the relay 25 energizing, the circuit of the pilot lamp 74 is closed, thus displaying the same 40 to indicate to the operator that a subscriber desires to make a call. The energization of the slow-acting relay 23 also connects an additional ground connection to the holding trunk 66 and the line switching relay 24 45 from ground G^{15} through the contact 150. No circuit is closed through the relay 24 at this time, owing to the side switch wiper 33 being in the first position at this time. The relay 23 prevents the release of the connection as far as it has gone should the calling subscriber operate his receiver hook up and down while the operator at the main office is making the call, for this relay being slow-acting does not deenergize as quickly as the 50 line relay 21, and thus maintains the circuit of the holding winding closed.

Upon the signal 74 being displayed, the operator inserts the plug P into the jack J in the usual manner, operates the listening key K and asks the calling subscriber the number of the desired line. Upon the plug P being inserted into the jack J, the circuits of the relays 76 and 191 are simultaneously closed and the lamp 74 is extinguished by 55 the deenergization of the relay 25. If the

desired number, which we have assumed to be 220, is in the same semi-automatic sub-exchange as the calling subscriber, the operator operates the calling device key K', which cuts the relay 76 out of the circuit and 60 cuts the calling device springs L into the circuit, and then proceeds to call in the usual manner. As soon as the key K' is operated to include the calling device L in the circuit, the relay 76 deenergizes, allowing its armature to drop back and again closing the circuit of the lamp 174 at the contact 175. The operator then operates the calling device to open and close the springs L twice to thus 65 send the impulses for the first digit 2 over the line to operate the first selector H. The circuit of the relay 26 is thus broken twice, which in turn twice breaks the circuit of the relay 28 at the contact 78. The armature of the relay 28 falls back a corresponding 70 number of times. The relay 29 being slow-acting does not deenergize during the momentary deenergization of the relay 28 and a circuit is closed twice extending from ground G^6 through the private relay 31 in 75 series with the vertical magnet 20 and through the side switch wiper 33 to battery and thence to ground. The vertical magnet 20 operates to raise the shaft wipers 35, 36 and 37 two steps, opposite the row of contacts in which terminate the trunk lines leading to the connector I. After the last of the vertical impulses has been delivered, the slow-acting relay 31, in series with the vertical magnet, deenergizes, thereby breaking 80 the circuit of the private magnet 30. The armature of the magnet falls back to release the side switch from first to second position, whereby a circuit is closed through the rotary magnet in series with the rotary interrupter 32, which together operate to rotate the shaft wipers 35, 36 and 37 onto an idle trunk line. After the wipers come to rest, the side switch is tripped to third position, 85 whereby a circuit is closed from ground G^3 through the line switching relay 24 and through the side switch wiper 33 to the battery lead 100. Upon the line switching relay 24 energizing, its springs are operated to open the circuit of the relay 26 to thus 90 balance the line and to cut the negative and positive lines through to the connector I, energizing the two line relays 51^a and 52. The circuit for the latter relay extends from ground G^7 through said coil, conductor 80, 95 line wiper 36, springs 81, conductor 90, through the jack and plug of the cord circuit C and through the relay 191 to the battery B'. The circuit of the former extends from ground G^{10} (Fig. 1) through the relay 125 75, calling device springs L and the key K', through the plug P and the jack J of the cord circuit, conductor 91, springs 82, conductor 83, side switch wiper 43, springs 85 and through the line relay 51^a to the bat- 130

tery B. Upon the side switch wiper 34 (Fig. 1) passing to third position, ground potential from ground G^{25} is placed on all the corresponding private contacts that are in 5 multiple with the contact on which the wiper 37 is resting, to prevent other wipers coming to rest on this trunk.

The operator now operates the dial for the tens digit 2, whereby the springs L of 10 the calling device are momentarily opened twice. It will be seen from Figs. 1 and 2 that the circuit of the line relay 52 is maintained closed the entire length of time the plug P is inserted into the jack J (Fig. 1). 15 Therefore, said relay is energized, retaining its armature and springs in an operated position. Upon the relay 51^a energizing, a circuit is closed from ground G^{11} through the contact springs 93 and 92, contact springs 20 94 of the relay 52 and through the slow-acting release relay 55 to the battery B. When the relay 55 is once energized, it forms a locking circuit for itself from ground G^{12} through the contact 106 of its 25 own springs and through the contact of springs 94, thence through its own winding to the battery B. Upon the springs of the calling device again being opened twice momentarily, the line relay 51^a is deenergized 30 a corresponding number of times to operate the vertical magnet in the usual manner to raise the shaft wipers 38, 39 and 40 two steps. The slow-acting private relay 95 is in series with the vertical magnet 41 and 35 upon the last impulse of this series being delivered, this relay deenergizes, thereby breaking the circuit of the private magnet 47, allowing the side switch to pass from first to second position and transferring 40 battery current from the vertical magnet to the rotary magnet. The calling device is now operated for the third digit 0, transmitting ten impulses over the line and operating the rotary magnet 42 to rotate the 45 shaft wipers 38, 39 and 40 around ten steps. After the last impulse of the series has been delivered, the private magnet again deenergizes and the side switch passes to third position. At this time the shaft wipers are 50 resting on the desired contact, and upon the side switch wiper 46 passing to third position, the circuit through the bridge-cut-off relay 98 of the line switch D' is closed, which energizes and presses together the 55 springs 99, thus completing the connection to the substation A'. Upon the side switch wiper 44 passing to third position, a circuit is closed from battery B through said side switch wiper, contact of the springs 101, 60 and through the relay 51 to the interrupter machine 102 to ground G^{13} , thereby intermittently energizing the relay 51 to disconnect the calling line from the called line at the springs of said relay, and to place the 65 ringing generator M across the called line,

The ringing generator M sends ringing current over the called subscriber's line to ring the bell at the substation. When the operator has finished calling, she restores the key K' to its normal position, thereby cutting out of the circuit the resistance coil 75 and cutting in the cord circuit relay 76. Since the side switch wiper 43 (Fig. 2) is 70 in third position, the circuit including the relay 76 is open at the springs 155 of the back-bridge relay 48. Therefore, the contact spring 175 remains closed and the line lamp 174 remains lighted. Upon the called subscriber taking his receiver off the switch hook to answer the call, the back-bridge relay 80 is energized in the usual manner to close the circuit of the ringing cut-off relay 50. The circuit of the relay 48 extends from ground G^{12} through the contact 106, through the lower winding of the relay 48, contacts 85 107 and 108, through the called subscriber's telephone, contact 99, contacts 110 and 111 of the relays 51 and 47, respectively, side switch wiper 45, through the upper winding of the relay 48 and through battery B to 90 ground G. The circuit of the relay 50 extends from ground G^{12} over part of the circuit already traced, through the contact 105 and relay 50 and the side switch wiper 44 to the battery B. When once this relay 95 is energized it remains locked by the springs 114 making contact. This locking circuit is to prevent the called subscriber's bell from 100 ringing again should he hang up his receiver before the calling subscriber has replaced his receiver. The energization of the back-bridge relay also operates its springs to close the circuit through the line relay 76 in the cord circuit of the main office (Fig. 1), said circuit extending from ground G^{26} 105 through said relay, key K', plug P and the jack J, contact 82 of the relay 24, conductor 83, side switch wiper 43, contact 155 and through the relay 51^a to battery B. Therefore, it is seen that as soon as the called 110 subscriber answers the call, the operator is notified of this fact by the lamp 174 being extinguished.

Should the called subscriber's line be busy, there will be a guarding ground potential 115 on the contact on which the private wiper 40 comes to rest, retaining the private magnet in an operated position to keep the lines open at the contacts 107 and 111. The busy relay 53 is energized and the usual busy tone 120 from the busy machine S is thrown back over the calling subscriber's line. The busy circuit just referred to is well known in the art and it is thought unnecessary to describe the same more fully in this specification.

To release the connection after the conversation has been completed, the called subscriber gives the operator at the main office the disconnect signal in the following manner: Upon returning his receiver to the 125 130

switch hook, the circuit of the back-bridge relay 48 is broken at the springs 170. This circuit was traced when the called subscriber answered the call. Upon the de-energization of the relay 48, the line relay 76 of the cord circuit C (Fig. 1) is deenergized by the breaking of the contact springs 155. This circuit extends from ground G²⁰ through the line relay 76, key K', plug P and the jack J, conductor 91, springs 82, conductor 83, side switch wiper 43, springs 155 and through the line relay 51^a of the connector to battery B. Upon the relay 76 in the cord circuit C deenergizing, the lamp 174 is lighted and the usual disconnect signal is received by the operator, whereupon she removes the plug P from the jack J, breaking the circuit of the relay 22, provided, of course, that the calling subscriber has also restored the receiver to the hook, which deenergizes and breaks the circuit of the slow-acting relay 23. Upon this relay deenergizing, the ground connection G¹⁵ is taken from the line switching relay 24, which deenergizes to disconnect the line conductors at the springs 82 and 81. At the same time a circuit is closed at the springs 159 of the relay 24, through the release magnet 160 and off-normal springs 161 to the battery lead 100. Upon the release magnet 160 energizing, the switch shaft is returned to its normal position, and as soon as it reaches its normal position it opens the contact of the off-normal springs 161, thereby allowing the release magnet to deenergize. Also when the springs 150 of the relay 23 break contact, the circuit of the holding coil 15 of the line switch D is broken, which deenergizes and allows the plunger arm 10 to return to its normal position, together with the plunger, thereby breaking the line extension at the bank springs 2-9. Upon the selector H thus being released, the line relays 51^a and 52 of the connector switch I are deenergized, the springs of the latter breaking their contact to open the circuit of the release relay 55. This relay, as in the selector H, deenergizes to close the circuit of the release magnet 54, releasing the switch in the well-known manner and leaving the line in readiness for further use.

In the foregoing it has been explained how the operator calls back over the same trunk line over which the signal is received in order to call the subscriber called for when his line terminates in the same sub-exchange as that of the calling subscriber. If the subscriber called for had been a subscriber of the main exchange, the connection would have been completed by the insertion of the calling plug P' of the cord C into a multiple jack of the line in the usual manner.

In a system of the character described herein there would be suitable trunk lines, in addition to those shown, leading from the

main exchange to automatic switches in the sub-exchange for the purpose of establishing connection between calling subscribers of the main exchange and called subscribers of the sub-exchange. As trunks for this purpose are known and do not form a feature of the present invention, it is not thought necessary to illustrate the same herein.

It will thus be seen that I have devised a very efficient form of semi-automatic district system in which each trunk to which the subscribers' individual switches have access has a branch leading to the operator's switchboard, as well as a branch leading to an individual selector switch in the district exchange. It will furthermore be seen that the trunk lines which are employed for extending the talking connection are the same trunk lines which are employed for signaling the operator and for transmitting the impulses back from the operator's board for the purpose of operating the automatic switches to connect with a called subscriber.

While I have illustrated and described my invention in connection with a semi-automatic system of a particular type, it will, of course, be understood that I do not wish to limit myself to the particular system shown and described, but that many other forms of automatic switches and operators' cord circuits can be employed without in any way departing from the spirit and intent of my invention.

What I claim as my invention is:—

1. In a telephone system, a trunk line, 100 having two branches having a common terminal, means for extending a talking connection from said terminal over either of said branches, an automatic switch associated with one of said branches, a relay connected 105 with said trunk, means for transmitting impulses back over the other branch of said trunk to operate said relay, means controlled by the operation of said relay for operating said automatic switch and means controlled 110 by the operation of said switch for breaking the circuit of said relay.

2. In a telephone system, a trunk line having two branches having a common terminal, 115 means for extending a talking connection from said terminal over either of said branches, an automatic switch associated with one of said branches, said switch having contact arms normally disconnected from said trunk, a relay normally connected with 120 said trunk, means for transmitting impulses back over the other branch to operate said relay, means controlled by said relay for controlling the operation of said switch, and means controlled by the operation of said 125 switch for connecting said switch arms with said trunk and for breaking the circuit of said relay.

3. In a telephone system, a manual switchboard, an automatic switch, a trunk line hav-

ing two branches having a common terminal, one of said branches leading directly to a jack in said switchboard and the other to said automatic switch, means for seizing said 5 common terminal, a condenser in said trunk, a relay bridged across said trunk on one side of said condenser, a signal at said switchboard controlled by said relay, and means for transmitting impulses back over said 10 trunk from said manual switchboard to operate said automatic switch.

4. In a telephone system, a manual switchboard, an automatic switch, a trunk line having two branches having a common terminal, one of said branches leading directly to a jack in said switchboard and the other to 15 said automatic switch, means for seizing said common terminal, a condenser in said trunk, a relay bridged across said trunk on one side of said condenser, a signal at said switchboard controlled by said relay, a second relay connected with said trunk on the other side of said condenser, means at said 20 manual switchboard for intermittently energizing said second relay, and means controlled by the operation of said second relay for controlling the operation of said 25 automatic switch.

5. In a telephone system, an automatic 30 switch, a trunk line having two branches having a common terminal, one of said branches leading to said automatic switch and the other of said branches terminating in a spring jack, an operator's cord circuit 35 adapted to be connected with said jack, means for seizing said common terminal for extending a talking connection over either of said branches, a signal associated with said jack adapted to be displayed upon seizure 40 of said trunk, means for rendering said signal inoperative when the cord circuit is connected with said jack, means in said cord circuit for transmitting impulses back over said trunk to operate said automatic switch while 45 said connection is extended to said common terminal, and lines divided into groups extending from said automatic switch, said switch having motion in one plane to select groups and motion in a plane at right angles 50 thereto to find a line in a selected group.

6. In a telephone system, a plurality of subscribers' lines, a trunk line, a manual switchboard, means for extending a connection from one of said subscribers' lines over 55 said trunk to said manual board, means for extending said connection from said board to a second of said subscribers' lines, automatic switches for extending a connection to another of said subscribers' lines, means at 60 said manual board for transmitting impulses back over said trunk to operate said switches, and lines divided into groups extending from said automatic switches, said switches having motion in one plane to select 65 groups and motion in a plane at right angles thereto to find a line in a selected group.

angles thereto to find a line in a selected group.

7. In a telephone system, a trunk line having two branches having a common terminal, means for extending a talking connection 70 from said terminal over either of said branches, an automatic switch associated with one of said branches, a relay connected with said trunk, means for transmitting impulses back over the other branch of said 75 trunk to operate said relay, means controlled by the operation of said relay for operating said automatic switch, means controlled by the operation of said switch for breaking the circuit of said relay, and lines divided into 80 groups extending from said automatic switch, said switch having motion in one plane to select groups and motion in a plane at right angles thereto to find a line in a selected group. 85

8. In a telephone system, a trunk line having two branches having a common terminal, means for extending a talking connection from said terminal over either of said branches, an automatic switch associated 90 with one of said branches, said switch having contact arms normally disconnected from said trunk, a relay normally connected with said trunk, means for transmitting impulses back over the other branch to operate 95 said relay, means controlled by said relay for controlling the operation of said switch, means controlled by the operation of said switch for connecting said switch arms with said trunk and for breaking the circuit of 100 said relay, and lines divided into groups extending from said automatic switch, said switch having motion in one plane to select groups and motion in a plane at right angles 105 thereto to find a line in a selected group. 110

9. In a telephone system, a trunk line having two branches having a common terminal, means for extending a talking connection from said terminal over either of said branches, automatic switches associated with 110 one of said branches, a condenser in said trunk, a relay connected with said trunk on one side of said condenser, means for transmitting impulses back over the second branch 115 of said trunk to operate said relay, means controlled by the operation of said relay for controlling the operation of said automatic switches, and lines divided into groups extending from said automatic switches, said switches having motion in one plane to select 120 groups and motion in a plane at right angles thereto to find a line in a selected group. 125

10. In a telephone system, a manual switchboard, an automatic switch, a trunk line having two branches having a common terminal, one of said branches leading directly to a jack in said switchboard and the other to 130 said automatic switch, means for seizing said common terminal for extending a connection over either of said branches, a 135

- condenser in one side of said trunk, a relay connected with said trunk on one side of said condenser, means at the manual switchboard for transmitting impulses back over one branch of said trunk to operate said relay, means controlled by the operation of said relay to control the operation of said automatic switch, whereby a talking circuit is set up over the said common terminal through the medium of said manual switchboard, and lines divided into groups extending from said automatic switch, said switch having motion in one plane to select groups and motion in a plane at right angles thereto to find a line in a selected group. 5
11. In a telephone system, a manual switchboard, an automatic switch, a trunk line having two branches having a common terminal, one of said branches leading directly to a jack in said switchboard and the other to said automatic switch, means for seizing said common terminal, a condenser in said trunk, a relay bridge across said trunk on one side of said condenser, a signal at said switchboard controlled by said relay, means for transmitting impulses back over said trunk from said manual switchboard to operate said automatic switch, and lines divided into groups extending from said automatic switch, said switch having motion in one plane to select groups and motion in a plane at right angles thereto to find a line in a selected group. 10
12. In a telephone system, a manual switchboard, an automatic switch, a trunk line having two branches having a common terminal, one of said branches leading directly to a jack in said switchboard and the other to said automatic switch, means for seizing said common terminal, a condenser in said trunk, a relay bridged across said trunk on one side of said condenser, a signal at said switchboard controlled by said relay, a second relay connected with said trunk on the other side of said condenser, means at said manual switchboard for intermittently energizing said second relay, means controlled by the operation of said second relay for controlling the operation of said automatic switch, and lines divided into groups extending from said automatic switch, said switch having motion in one plane to select groups and motion in a plane at right angles thereto to find a line in a selected group. 15
13. In a telephone system, a subscriber's line, a plurality of trunk lines, a trunk-selecting switch adapted to make connection with an idle one of said trunks, each of said trunks having two branches, a spring jack at the end of one of said branches, an automatic switch in which the other branch terminates, a cord circuit associated with said spring jack having means for transmitting impulses back over one branch to operate the automatic switch associated with the other branch of said trunk, and lines divided into groups extending from said automatic switch, said switch having motion in one plane to select groups and motion in a plane at right angles thereto to find a line in a selected group. 20
14. In a telephone system, a subscriber's line, a plurality of trunk lines, a trunk-selecting switch adapted to make connection with an idle one of said trunks, each of said trunks having two branches, a spring jack at the end of one of said branches, an automatic switch in which the other branch terminates, a signal associated with each jack, means for displaying the corresponding signal when said trunk-selecting switch makes connection with one of said trunks, means associated with said selected jack for transmitting impulses back over one branch of the selected trunk to operate the automatic switch associated with the other branch of said trunk to extend a connection over said common terminal, and lines divided into groups extending from said automatic switch, said switch having motion in one plane to select groups and motion in a plane at right angles thereto to find a line in a selected group. 25
15. In a telephone system, a subscriber's line, a plurality of trunk lines, a trunk-selecting switch adapted to make connection with an idle one of said trunks, each of said trunks having two branches, a spring jack at the end of one of said branches, an automatic switch in which the other branch terminates, a signal associated with each jack, means for displaying the corresponding signal when said trunk-selecting switch makes connection with one of said trunks, a cord circuit with a plug adapted to be connected with said selected jack, means controlled by the insertion of said plug in said jack for rendering said signal inoperative, an impulse transmitter associated with said cord circuit for transmitting impulses back over one branch of said selected trunk to operate the automatic switch associated with the other branch of said trunk, and lines divided into groups extending from said automatic switch, said switch having motion in one plane to select groups and motion in a plane at right angles thereto to find a line in a selected group. 30
16. In a telephone system, a trunk line having two branches having a common terminal, means for extending a talking connection between two subscribers via said terminal over either of said branches, automatic progressively movable switches associated with one of said branches, means for transmitting impulses back over the other branch to operate said automatic switches, and a signal associated with said other 35

branch operated when a connection is extended thereover.

17. In a telephone system, a local exchange and a distant exchange, a trunk line having two branches, having a common terminal, means for extending a talking connection from said terminal over one of said branches to the subscribers of the local exchange and over the other branch to the subscribers of the distant exchange, automatic progressively movable switches associated with one of said branches, means for transmitting impulses back over the other branch to operate said automatic switches, and a signal associated with said other branch operated when a connection is extended thereover.

18. In a telephone system, a trunk line having two branches having a common terminal, means for extending a talking connection from said terminal over either of said branches, an automatic switch associated with one of said branches, a relay connected with said trunk, means for transmitting impulses back over the other branch of said trunk to operate said relay, means controlled by the operation of said relay for operating said automatic switch, means controlled by the operation of said switch for breaking the circuit of said relay, a signal associated with one of the branches, and means under the control of the automatic switch in the other branch for rendering said signal inoperative over the trunk.

19. In a telephone system, a trunk line having two branches having a common terminal, means for extending a talking connection from said terminal over either of said branches, an automatic switch associated with one of said branches, said switch having contact arms normally disconnected from said trunk, a relay normally connected with said trunk, means for transmitting impulses back over the other branch to operate said relay, means controlled by said relay for controlling the operation of said switch, means controlled by the operation of said switch for connecting said switch arms with said trunk and for breaking the circuit of said relay, a signal associated with one of the branches, and means under the control of the automatic switch in the other branch for rendering said signal inoperative over the trunk.

20. In a telephone system, an automatic switch, a trunk line having two branches having a common terminal, one of said branches leading to said automatic switch and the other of said branches terminating in a spring jack, an operator's cord circuit adapted to be connected with said jack, means for seizing said common terminal for extending a talking connection over either of said branches, a signal associated with the branch terminating in said jack adapted to be displayed upon seizure of said trunk,

means for rendering said signal inoperative when the cord circuit is connected with said jack, means in said cord circuit for transmitting impulses back over said trunk to operate said automatic switch, lines divided into groups extending from said automatic switch, said switch having motion in one plane to select groups and motion in a plane at right angles thereto to find a line in a selected group, and means under the control of said automatic switch in the other branch for rendering said signal inoperative over the trunk.

21. In a telephone system, a trunk line having two branches having a common terminal, means for extending a talking connection from said terminal over either of said branches, an automatic switch associated with one of said branches, a relay connected with said trunk, means for transmitting impulses back over the other branch of said trunk to operate said relay, means controlled by the operation of said relay for operating said automatic switch, means controlled by the operation of said switch for breaking the circuit of said relay, lines divided into groups extending from said automatic switch, said switch having motion in one plane to select groups and motion in a plane at right angles thereto to find a line in a selected group, a signal associated with one of the branches, and means under the control of the automatic switch in the other branch for rendering said signal inoperative over the trunk.

22. In a telephone system, a trunk line having two branches having a common terminal, means for extending a talking connection from said terminal over either of said branches, an automatic switch associated with one of said branches, said switch having contact arms normally disconnected from said trunk, a relay normally connected with said trunk, means for transmitting impulses back over the other branch to operate said relay, means controlled by said relay for controlling the operation of said switch, means controlled by the operation of said switch for connecting said switch arms with said trunk and for breaking the circuit of said relay, lines divided into groups extending from said automatic switch, said switch having motion in one plane to select groups and motion in a plane at right angles thereto to find a line in a selected group, a signal associated with one of the branches, and means under the control of said automatic switch in the other branch for rendering said signal inoperative over the trunk.

23. In a telephone system, a trunk line having two branches having a common terminal, means for extending a talking connection from said terminal over either of said branches, automatic switches associated with one of said branches a condenser in said trunk,

5 a relay connected with said trunk on one side of said condenser, means for transmitting impulses back over the second branch of said trunk to operate said relay, means controlled by the operation of said relay for controlling the operation of said automatic switches, lines divided into groups extending from said automatic switches, said switches having motion in one plane to select groups and motion in a plane at right angles thereto to find a line in a selected group, a signal associated with one of the branches, and means under the control of an automatic switch in the other branch for rendering said signal 10 inoperative over the trunk.

15

24. In a telephone system, a subscriber's line, a plurality of trunk lines, a trunk-selecting switch adapted to make connection with an idle one of said trunks, each of said trunks having two branches, a spring jack at the end of one of said branches, an automatic switch in which the other branch terminates, means associated with said spring jack for transmitting impulses back over one branch to operate the automatic switch associated with the other branch of said trunk whereby a talking circuit is set up over the said common terminal through the medium of the manual switchboard, lines divided into groups extending from said automatic switch, said switch having motion in one plane to select groups and motion in a plane at right angles thereto to find a line in a selected group, a signal associated with each of the spring jacks, and means under the control of said automatic switch in the other branch for rendering said signal inoperative over the trunk.

25. In a telephone system, a subscriber's
40 line, a plurality of trunk lines, a trunk-selecting switch adapted to make connection with an idle one of said trunks, each of said trunks having two branches, a spring jack at the end of one of said branches, an automatic switch in which the other branch terminates, a signal associated with each branch terminating in a jack, means for displaying the corresponding signal when said trunk-selecting switch makes connection
45 50 with one of said trunks, means associated with said selected jack for transmitting impulses back over one branch of the selected trunk to operate the automatic switch associated with the other branch of said trunk, lines
55 divided into groups extending from said automatic switch, said switch having motion in one plane to select groups and motion in a plane at right angles thereto to find a line in a selected group, and means under
60 the control of said automatic switch in the other branch for rendering said signal inoperative over the trunk.

26. In a telephone system, a subscriber's

line, a plurality of trunk lines, a trunk-selecting switch adapted to make connection with an idle one of said trunks, each of said trunks having two branches, a spring jack at the end of one of said branches, an automatic switch in which the other branch terminates, a signal, associated with each branch terminating in a jack, means for displaying the corresponding signal when said trunk-selecting switch makes connection with one of said trunks, a cord circuit with a plug adapted to be connected with said selected jack, means controlled by the insertion of said plug in said jack for rendering said signal inoperative, an impulse transmitter associated with said cord circuit for transmitting impulses back over one branch of said selected trunk to operate the automatic switch associated with the other branch of said trunk, lines divided into groups extending from said automatic switch, said switch having motion in one plane to select groups and motion in a plane at right angles thereto to find a line in a selected group, and means under the control of said automatic switch in the other branch for rendering said signal inoperative over the trunk. 90

27. In a telephone system, a trunk line having two branches having a common terminal, means for extending a talking connection between two subscribers via said terminal over either of said branches, automatic progressively movable switches associated with one of said branches, means for transmitting impulses back over the other branch to operate said automatic switches, a signal associated with one of the branches, and means under the control of an automatic switch in the other branch for rendering said signal inoperative over the trunk. 95 100

28. In a telephone system, a local exchange and a distant exchange, a trunk line having two branches, having a common terminal, means for extending a talking connection from said terminal over one of said branches to the subscribers of the local exchange and over the other branch to the subscribers of the distant exchange, automatic progressively movable switches associated with one of said branches, means for transmitting impulses back over the other branch to operate said automatic switches, a signal associated with one of the branches, and means under the control of an automatic switch in the other branch for rendering said signal inoperative over the trunk. 105
